UNITED STATES PATENT OFFICE.

WILLIAM R. FOX, OF GRAND RAPIDS, MICHIGAN.

RIBBON MECHANISM FOR FRONT-STRIKE TYPE-WRITING MACHINES.

No. 880,648.

Specification of Letters Patent.

Patented March 3, 1908.

Application filed March 16, 1907. Serial No. 362,733.

To all whom it may concern:

Be it known that I, WILLIAM R. FOX, a citizen of the United States, residing at Grand Rapids, in the county of Kent, State of Michigan, have invented certain new and useful Improvements in the Ribbon Mechanism for Front-Strike Type-Writing Machines, of which the following is a specification.

This invention relates to improvements in mechanisms and devices for front strike type-writing machines.

The objects of the invention are to provide an improved mechanism and means for controlling the ribbon vibrator, so that the full width of the ribbon may be utilized and also so that a party-colored ribbon may be utilized, and so that the ribbon vibrator can be depressed and not swing the ribbon to the printing position when it is desired to make stencils, as for mimeograph work.

Other objects relate to improvements in the arrangement of the parts and particularly to the construction of the improved ribbon guide.

Objects pertaining to details of construction and mechanism will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which:

Figure 1 is a detail sectional view of the portion of a typewriting machine embodying the features of my invention, taken on a line 1-1 of Fig. 2; Fig. 2 is a detail sectional elevation view of the front portions of a typewriting machine, taken on a line corresponding to line 2-2 of Fig. 1, showing the relation of the ribbon vibrator and of the various mechanisms for securing the operation, control and adjustment of the ribbon, referred to, the oscillator for the ribbon vibrator being adjusted for utilizing the full width of the ribbon; Fig. 3 is a similar sectional view to that appearing in Fig. 2, showing the ribbon oscillator out of gear and showing the mechanism adjusted for the use of a party-colored ribbon; Fig. 4 is a detail sectional view, taken on a line corresponding to line 4-4 of Fig. 3, showing the shifting means for using the party-colored ribbon; Fig. 5 is a

plan view of the ribbon vibrator, the position of the ribbon being indicated by the dotted line; Fig. 6 shows the link connection and automatic lock of the adjusting mechanism for utilizing a party-colored ribbon, and the stop means which prevents its interfering with the ribbon oscillator; Fig. 7 is a detail view of the yielding connection between the actuating lever and the ribbon vibrator; and Fig. 8 shows the details of the connection between the lever arm 37 and the yielding arm 32.

In the drawing, the sectional views are taken looking in the direction of the little arrows at the ends of the section lines, and similar numerals of reference refer to similar parts throughout the several views.

Referring to the numbered parts of the drawing, the frame 1 is of the usual form for use in the Fox typewriter. The ribbon spools 3 are supported on suitable transverse shafts 2-2 and are operated by any usual or preferred mechanism for the purpose. The invention here not pertaining to the means for driving the ribbon spools, the same is not illustrated.

Guide spools 6-6, supported on brackets 5-5, are at each side of the machine for receiving and guiding the typewriter ribbon. The ribbon is deflected and twisted at substantially right angles on its axis and inserted into the ribbon vibrator 40. The ribbon guide 40 is formed of sheet metal integral with the arms 39-39, being turned downwardly therefrom, and the arms are secured to the rock-shaft 38. The rock shaft 38 is supported on suitable bearings, preferably pointed screws, towards the front of the machine.

The ribbon guide 40 is slotted to form the intermediate upwardly projecting fingers 40', separated from each other at the printing point, over which the ribbon is looped. The ribbon is retained between these fingers and the body of the vibrator. The fingers, as before remarked, are separated sufficiently to permit the stroke of the type between them. The ribbon is arranged underneath the angle of the arms 39, at their point of connection to the guide 40, and is prevented from upward displacement by that means.

A downwardly depending lever arm 37 is secured to the rock shaft 38, and is the lever arm by which the ribbon vibrator is actuated. This lever arm is curved or offset at its lower end for the purpose of co-acting in a variable

stop means for controlling the movements of the vibrator when it is desired to use a party-colored ribbon:

A swinging arm 7 is suspended from the bracket 5, and, on the lower end, is provided with a curved contact shoe 8 for contacting with the face cam 4 secured to the side of the ribbon spool. A link 9 is pivoted to this arm 7, and is provided with a slot 13 towards its forward end, into which extends an actuating pin 13'; and a stop 10 on this link 9 limits the movements of the link 9 on the pivot on the arm 7. An adjustable stop 14 is on the rear end of the link 9, the same being adjustable by suitable lock nuts. A flange 11 is turned at right angles to the link 9 to receive this adjustable stop 14.

On a rock shaft 12, controlled by the knurled head 53, is an arm 12' which carries the pin 13', acting in the slot 13 of the link 9. A notch is on the edge of the arm 12', and a yielding spring catch 51 is secured to the typewriter frame above for supporting this arm 12' yielding in its elevated position.

The stop 14 on the link 9 is arranged to swing into the path of motion of the lever arm 37, as seen in Fig. 2. When the device is in the position indicated in Fig. 2, it will be noted that, as the spool 3 revolves, the face cam 4 will act upon the shoe 8, and the stop 14 will be moved back and forth as a consequence, depending on the position of the cam 4. It moves freely because the link 9 is free to move over the pin 13', the slot 13 permitting the movement. This moves the stop 14 back and forth and consequently controls and varies the movements of the lever arm 37, thereby permitting the ribbon vibrator to move different distances as the ribbon spool rotates with its face cam 4 and thereby secures the oscillation of the ribbon vibrator which oscillates the ribbon and utilizes the full width thereof.

As before remarked, the lower end of the lever arm 37 is curved, the extreme lower end 37' being offset from the portion of this lever a little above the same.

When a party-colored ribbon is used, one edge is black and the other is red, or some other color, as may be desired, and it is obvious that by controlling the movements of the vibrator 40, the upper part or edge or the lower part or edge of the ribbon may be utilized. The party-colored ribbon is indicated in Fig. 1. A stop 17 is provided which is adjustable up and down on the plate 15 to permit the main part of the lever arm 37, or its offset part 37', to contact with the stop, thus controlling the height to which the ribbon will be raised and, by so doing, using either the upper or lower part. The stop 17 is carried on the swinging plate 15, the motion up and down of which is limited by the pin 18 on the frame, extending into the slot 18' on the plate 15. A link

20 depends from this oscillating plate 18 and is secured to the levers 27 and 29 by a pivot 31 common to both levers. The lever 27 is fulcrumed at 28 at its rear end and is provided at its front end with a key button so that an operator, in depressing the key 27, will bring the plate 15 down to the limit of its motion by the connection. The lever 29 is fulcrumed at 30, at pivot 31 in front of the fulcrum, and connects to the lever 20 by the pivot 31 back of its fulcrum 30, and is provided with a key button at its front end so that depressing the front end of the lever 29 throws the link 20 upwards and elevates the plate 15.

The plate 15 is locked automatically in position by the spring 46, which embraces the pin 18 and is connected to the pivot pin 20' which connects the link 20 to the plate 15, and, as this is thrown up past the center or down past the center, as the case may be, by the operation of the levers, it will be seen that the same is held normally in position. On the upper rear corner of the plate 15 is a stop 15' which, when the plate 15 is elevated, contacts with the arm 12' and prevents the ribbon oscillator being thrown into position when the lever 29 is depressed. By ribbon oscillator is meant the parts consisting of the arms 39 and downwardly bent portion 40 supported on a suitable rock shaft 38 arranged in the front part of the machine. This insures the proper relation of these parts, so that the full oscillation of the ribbon is secured when the ribbon oscillator is thrown into position, and the ribbon oscillator can only be thrown into position when the key 27 is depressed. When the ribbon oscillator is in gear, the arm 12' is thrown down to the position indicated in Fig. 2, and it engages the stop 15' and insures that the party-colored mechanism cannot be operated by the ribbon oscillator when in use.

When it is desired to depress the ribbon vibrator, for the purpose of making stencils, I provide a lever 41, controlled by the plunger 43, terminating in a button 43' at the front of the machine. A spring 44 holds this plunger normally upward, so that the notches thereon engage the catch 45. Simply pushing this button swings the lower end of the lever 40 inward and the upper portion out against the lever arm 37, thus holding the ribbon vibrator in the depressed position. When it is desired to release the ribbon vibrator, the button 43' is merely depressed, when the spring 44, owing to its oblique position, throws the plunger properly outward and releases the vibrator.

From the description of these various parts, it must be very clear that the actuating means for the lever-arm 37 must be yielding. This I accomplish by providing a suitable spring mechanism. A rock shaft

24 is supported by suitable pivoted brackets 25 on the common cross-bar 26 of the machine. Arms 23 extend towards the arm of the machine therefrom and are provided 5 with downwardly depending links 47 which connect to a bar 48 beneath the key lever 49. Secured to one of these levers 23 is an upwardly-extending plate 33 which is actuated by the movements of the levers 23, 10 which rock the rock shaft 24. A plate 32 is parallel therewith and extends upwardly therefrom and is slotted and receives the lever arm 37 loosely therein. On the plate 32 are a pair of pins 34—34 (see Fig. 7), 15 which extend through apertures in the plate 33. A central pin 35 extends through the same and is provided with a suitable nut at the end, and a coiled spring 36 acts between this nut and the plate 33 to hold the said 20 plate 32 yieldingly in position, so that the levers or arms 23 can operate a full stroke, and are thus provided with a yielding connection to the lever arm 37 on the rock shaft 38 which actuates the ribbon vibrator 25 or oscillator. The tension of this device is easily adjusted by the nut 35 referred to. It will thus be seen that the levers 23 can be fully depressed independent of the arm 32, which yields and, consequently, the movement of the connected parts is readily controlled by the stop means.

Having thus described my invention, what I claim as new and desire to secure by Letters Patent is:

35 1. In a ribbon mechanism for typewriters, the combination of the frame; a ribbon spool upon a suitable shaft; a face cam 4 on the face of the ribbon spool and rotatable therewith; a ribbon oscillator or vibrator consisting of 40 arm 39 and downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a swinging arm 7 pivoted in the upper part of the machine and terminating in a suitable shoe 8 at its lower end to rest against the 45 face cam; a horizontal link 9 carrying an adjustable stop 14 at its forward end, supported on a suitable flange 11, a slot 13 being formed in said link 9; a rock shaft 12 with a knurled button 53 at its outer end for actuating the same; arms 12' on the said rock shaft 12 with a pin 13' engaging the slot 13 in the link 9, whereby on rotating the shaft 12, the shoe 8 will be thrown into or out of contact with the cam 4, the stop 14 being 50 arranged to limit the motion of the lever-arm 37 in varying degree, owing to its actuation by the cam 4, thereby securing oscillation of the ribbon vibrator guide; a spring catch 51 for supporting the arm 12'; a swinging plate 60 55 15; a link 20 connected thereto; a pair of

levers 27—29 connected to the lower end of said link, the lever being fulcrumed back of the link and the lever 29 in front of the link, whereby the depressing of the said levers will raise or lower the said link; a spring 46 connected to the stop pin 18 operating in a suitable slot to limit the motion of the said plate 15 and lock it either side of the center automatically; a stop 17 carried by the said adjustable plate 15 for contacting with the 75 main part of the lever-arm 37, or the offset portion 37' therein, to permit the utilization of a party-colored ribbon; a stop 15' formed on the plate 15 for controlling the arm 12'; a stop formed on the arm 12' to control the 80 plate 15 whereby it is impossible to swing the one into position without first swinging the other out of position; a lever 41 with an offset portion 42 for contacting with the said lever-arm 37; a plunger 43 with suitable 85 notches on its upper side and having an actuating button 43' for controlling the said lever 41 for throwing the lever-arm 37 forward and depressing the ribbon guide out of the printing position; a spring 44 for throwing the said plunger 43 upwards to engage the catch 45; a rock shaft 24 in the lower front part of the machine, with a vertical plate 33 secured thereto; actuating levers 23 on the said rock shaft 24 extending toward the rear 95 of the machine; an actuating arm 32 slotted to engage the lever-arm 37; a pair of pins 34—34 extending through the said plate 33; a central pin 35 secured to the arm 32 and extending through the plate 33; a coiled 100 spring 36 on the pin 35 to hold the same yieldingly in position; a common bar beneath the key levers; and connections 47 from said common bar 48 to said levers 23, all coacting substantially as described and 105 for the purpose specified.

2. In a ribbon mechanism for typewriters, the combination of the frame; a ribbon spool upon a suitable shaft; a face cam 4 on the face of the ribbon spool and rotatable 110 therewith; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a swinging arm 7 pivoted 115 in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; arms 12' on the said rock shaft 12 with a pin 13' 120 engaging the slot 13 in the link 9, whereby on rotating the shaft 12, the shoe will be 125 130

- thrown out of or into contact with the cam 4, the stop 14 being arranged to limit the motion of the lever-arm 37 in varying degree, owing to its actuation by cam 4, thereby 5 securing oscillation of the ribbon vibrator guide; a spring catch 51 for supporting arm 12'; adjustable stop means for the lever-arm 37 with its offset portion; connections to the key levers at the front of the machine for 10 varying the stop to utilize party-colored ribbons; an adjustable stop with a lever connected to act upon the lever arm 37 and depress the ribbon guide below the printing point; a rock shaft 24 in the lower front part 15 of the machine, with a vertical plate 33 secured thereto; actuating levers 23 for said rock shaft 24 extending towards the rear of the machine; an actuating arm 32 slotted to engage the lever-arm 37; a pair of pins 34—34 extending through the said plate 33; a central pin 35 secured to the arm 32 and 70 extending through the plate 33; a coiled spring 36 on the pin 35 to hold the same yieldingly in position; a common bar 48 beneath the key levers; and connections 47 from said common bar 48 to said levers 23, 75 all coacting substantially as described and for the purpose specified.
4. In a ribbon mechanism for typewriters, the combination of the frame; a ribbon spool upon a suitable shaft; a face cam on the face 80 of the ribbon spool and rotatable therewith; a ribbon oscillator or vibrator consisting of arms 39 and the downwardly bent portion 40 supported on a suitable rock shaft 38; arranged in the upper front part of the ma- 85 chine; a downwardly-extending lever-arm 37 with its lower portion 37' offset from the main lever-arm to secure variation in movement, in conjunction with adjustable stop means; a swinging arm 7 pivoted in the upper part of the machine and terminating in a suitable shoe 8 at its lower end to rest against the face cam; a horizontal link 9 carrying an adjustable stop 14 at its forward end, sup- 90 ported on a suitable flange 11, a slot 13 being formed in said link 9; a rock shaft 12 with a knurled button 53 at its outer end for actuating the same; an arm 12' on the rock shaft 12 with a pin 13' engaging the slot 13 in the link 9, whereby on rotating the shaft 12, the shoe 8 will be thrown out of or into contact with the cam 4, the stop 14 being arranged to limit the motion of the lever-arm 37 in va- 95 rying degree, owing to its actuation by cam 4, thereby securing oscillation of the ribbon 100 vibrator guide; a spring catch 51 for sup- 105 porting arm 12'; adjustable stop means for the lever-arm 37 with its offset portion; an adjustable stop with a lever connected to act upon the lever-arm 37 and depress the rib- 110 bon guide below the printing point; a rock shaft 24 in the lower front part of the ma- 115 chine, with a vertical plate 33 secured thereto; actuating levers 23 on said rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 120 to hold the same yieldingly in position; a common bar 48 beneath the key levers; and connections 47 from said common bar 48 to said levers 23, all coacting substantially as 125 described and for the purpose specified.
5. In a ribbon mechanism for typewriters, the combination of the frame; a ribbon spool upon a suitable shaft; a face cam 4 on the face of the ribbon spool and rotatable therewith; a ribbon oscillator or vibrator consist- 130

ing of arms 39 and the downwardly bent portion 40 supported on a suitable rock shaft 38; arranged in the upper front part of the machine; a downwardly-extending lever-arm 5 37 with its lower portion 37' offset from the main lever-arm to secure variation in movement in conjunction with adjustable stop means; a swinging arm 7 pivoted in the upper part of the machine and terminating in a 10 suitable shoe 8 at its lower end to rest against the face cam; a horizontal link 9 carrying an adjustable stop 14 at its forward end, supported on a suitable flange 11, a slot 13 being formed in said link 9; a rock shaft 12 with a 15 knurled bottom 53 at its outer end for actuating the same; an arm 12' on the said rock shaft 12 with a pin 13' engaging the slot 13 in the link 9, whereby on rotating the shaft 12, the shoe 8 will be thrown out of or into 20 contact with the cam 4, the stop 14 being arranged to limit the motion of the lever-arm 37 in varying degree, owing to its actuation by cam 4, thereby securing oscillation of the 25 ribbon vibrator guide; a rock shaft 24 in the lower front part of the machine, with a vertical plate 33 secured thereto; actuating levers 30 23 on said rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 to hold the 35 same yieldingly in position; a common bar 48 beneath the key levers; and connections 47 from said common bar 48 to said levers 23, all coacting substantially as described and for the purpose specified.

6. In a ribbon mechanism for typewriters, the combination of the frame; a ribbon spool upon a suitable shaft; a ribbon oscillator or 40 vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to 45 secure variation in movement in conjunction with adjustable stop means; a variable stop means for the said lever-arm 37 controlled by a moving part of the machine, whereby oscillation of the ribbon is secured; a swinging plate 15; a link 20 connected thereto; a pair of levers 27—29 connected to the lower end of the said link, the lever 27 being fulcrumed back of the link and the lever 29 in front of 55 the link, whereby the depressing of the said levers will raise or lower the said link; a spring 46 connected to the stop pin 18 operating in a suitable slot to limit the motion of the said plate 15 and lock it either side of the center automatically; a stop 17 carried by 60 the said adjustable plate 15 for contacting with the main part of the lever-arm 37, or the offset portion 37' therein, to permit the utilization of a party-colored ribbon; a stop 15' 65 formed on the plate 15 for controlling the arm 12'; a stop formed on the arm 12' to control the plate 15 whereby it is impossible to swing the one into position without first swinging the other out of position; a lever 41 with an offset portion 42 for contacting with the said lever-arm 37; a plunger 43 with suitable notches on its upper side and having an actuating button 43' for controlling the said lever 41 for throwing the lever-arm 37 forward and depressing the ribbon guide out of 70 the printing position; a spring 44 for throwing the said plunger 43 upwards to engage the catch 45; a rock shaft 24 in the lower front part of the machine, with a vertical plate 33 secured thereto; actuating levers 75 23 on said rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 to hold the same yieldingly in position; a common bar 48 beneath the key levers; and connections 80 47 from said common bar 48 to said levers 23, all coacting substantially as described and for the purpose specified.

7. In a ribbon mechanism for typewriters, the combination of the frame; a ribbon spool upon a suitable shaft; a ribbon oscillator or 95 vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to 100 secure variation in movement in conjunction with adjustable means; a variable stop means for the said lever-arm 37 controlled by a moving part of the machine, whereby 105 oscillation of the ribbon is secured; adjustable stop means for the lever-arm 37 with its offset portion; connections to the key levers at the front of the machine for varying the stop to utilize party-colored ribbons; an adjustable stop with a lever connected to act upon the lever-arm 37 and depress the ribbon guide below the printing point; a rock shaft 24 in the lower front part of the machine with a vertical plate 33 secured thereto; actuating levers 110 23 on the rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 to hold the same yieldingly in position; a common bar 48 beneath the key levers; and connections 115 47 from said common bar 48 to said lever 23, all coacting substantially as described and for the purpose specified.

8. In a ribbon mechanism for typewriters, the combination of the frame; a ribbon spool upon a suitable shaft; a ribbon oscillator or 120

- vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a variable stop means for the said lever-arm 37 controlled by a moving part of the machine, whereby oscillation of the ribbon is secured; adjustable stop means for the lever-arm 37 with its offset portion; connections to the key levers at the front of the machine for varying the stop to utilize party-colored ribbons; a rock shaft 24 in the lower front part of the machine, with a vertical plate 33 secured thereto; actuating levers 23 on the rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 to hold the same yieldingly in position; a common bar 48 beneath the key levers; and connections 47 from the said common bar 48 to said levers 23, all coacting substantially as described and for the purpose specified.
30. 9. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a variable stop means for the said lever-arm 37 controlled by a moving part of the machine, whereby oscillation of the ribbon is secured; adjustable stop means for the lever-arm 37 with its offset portion; an adjustable stop with a lever connected to act upon the lever-arm 37 and depress the ribbon guide below the printing point; a rock shaft 24 in the lower front part of the machine, with a vertical plate 33 secured thereto; actuating levers 23 on the rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 to hold the same yieldingly in position; a common bar 48 beneath the key levers; and connections 47 from the said common bar 48 to said lever 23, all coacting substantially as described and for the purpose specified.
60. 10. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a variable stop means for the said lever-arm 37 controlled by a moving part of the machine, whereby oscillation of the ribbon is secured; a rock shaft 24 in the lower front part of the machine, with a vertical plate 33 secured thereto; actuating levers 23 on the rock shaft 24 extending towards the rear of the machine; an actuating arm 32 slotted to engage the lever-arm 37; a pair of pins 34—34 extending through the said plate 33; a central pin 35 secured to the arm 32 and extending through the plate 33; a coiled spring 36 on the pin 35 to hold the same yieldingly in position; a common bar 48 beneath the key levers; and connections 47 from the said common bar 48 to said levers 23, all coacting substantially as described and for the purpose specified.
11. In a ribbon mechanism for typewriters, the combination of the frame; a ribbon spool upon a suitable shaft; a face cam 4 on the face of the ribbon spool and rotatable therewith; a ribbon oscillator or vibrator consisting of arms 39 with the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a swinging arm 7 pivoted in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; arms 12' on the said rock shaft 12 with a pin 13' engaging the slot 13 in the link 9, whereby on rotating the shaft 12, the shoe 8 will be thrown into or out of contact with the cam 4, the stop 14 being arranged to limit the motion of the lever-arm 37 in varying degree, owing to its actuation by cam 4, thereby securing oscillation of the ribbon vibrator guide; a spring 120 catch 51 for supporting arm 12'; a swinging plate 15; a link 20 connected thereto; a pair of levers 27—29 connected to the lower end of the said link, the lever being fulcrumed back of the link and the lever 29 in front of the link, whereby the depressing of the said levers will raise or lower the said link; a spring 46 connected to the stop pin 18 operating in a suitable slot to limit the motion of the said plate 15 and lock it either side of the 130

center automatically; a stop 17 carried by the said adjustable plate 15 for contacting with the main part of the lever-arm 37, or the offset portion 37' therein, to permit the utilization of a party-colored ribbon; a stop 15' formed on the plate 15 for controlling the arm 12'; a stop formed on the arm 12' to control the plate 15 whereby it is impossible to swing the one into position without first 10 swinging the other out of position; a lever 41 with an offset portion 42 for contacting with the said lever-arm 37; a plunger 43 with suitable notches on the upper side and having an actuating button 43' for controlling the said 15 lever 41 for throwing the lever-arm 37 forward and depressing the ribbon guide out of the printing position; a spring 44 for throwing the said plunger 43 upwards to engage the catch 45; and a yielding means 20 with connections to be actuated from the key levers of the typewriter, whereby the extent of actuation is controlled, all coacting substantially as described and for the purpose specified.

12. In a ribbon mechanism for typewriters, the combination of the frame; a ribbon spool upon a suitable shaft; a face cam 4 on the face of the ribbon spool and rotatable therewith; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a swinging arm 7 pivoted in the upper part of the machine and terminating in a suitable shoe 8 at its lower end to rest against the face 25 cam; a horizontal link 9 carrying an adjustable stop 14 at its forward end, supported on a suitable flange 11, a slot 13 being formed in said link 9; a rock shaft 12 with a knurled button 53 at its outer end for actuating the same; an arm 12' on the said rock shaft 12 with a pin 13' engaging the slot 13 in the link 9, whereby on rotating the shaft 12, the shoe 8 will be thrown out of or into contact with the cam 4, the stop 14 being arranged to limit the motion of the lever-arm 37 in varying degree, owing to its actuation by cam 4, thereby securing oscillation of the ribbon vibrator guide; a spring catch 51 for supporting arm 12'; adjustable stop means for the 30 lever-arm 37 with its offset portion; connections to the key levers at the front of the machine for varying the stop to utilize party-colored ribbons; an adjustable stop with a lever connected to act upon the lever-arm 37 and depress the ribbon guide below the printing point; a yielding means with connections to be actuated from the key levers of the typewriter, whereby the extent of actuation is controlled.

13. In a ribbon mechanism for typewriters,

the combination of the frame; a ribbon spool upon a suitable shaft; a face cam 4 on the face of the ribbon spool and rotatable therewith; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a swinging arm 7 pivoted in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; an arm 12' on the said rock shaft 12 with a pin 13' engaging the slot 13 in the link 9, whereby on rotating the shaft 12, the shoe 8 will be thrown out of or into contact with the cam 4, the stop 14 being arranged to limit the motion of the lever-arm 37 in varying degree, owing to its actuation by cam 4, thereby securing oscillation of the ribbon vibrator guide; a spring catch 51 for supporting arm 12'; adjustable stop means for the lever-arm 37 with its offset portion; connections to the key levers at the front of the machine for varying the stop to utilize party-colored ribbons; and a yielding means with connections to be actuated from the key levers of the typewriter, whereby the extent of actuation is controlled, all coacting substantially as described and for the purpose specified.

14. In a ribbon mechanism for typewriters, the combination of the frame; a ribbon spool upon a suitable shaft; a face cam on the face of the ribbon spool and rotatable therewith; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a swinging arm 7 pivoted in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; an arm 12' on the said rock shaft 12 with a pin 13' engaging the slot 13 in the link 9, whereby on rotating the shaft 12, the shoe 8 will be thrown out of or into contact with the cam 4, the stop 14 being arranged to limit the motion of the lever-arm 37 in varying degree, owing to its actuation by cam 4, thereby securing oscillation of the ribbon vibrator guide; a spring catch 51 for supporting arm 12'; adjustable stop means for the lever-arm 37 with its offset portion; connections to the key levers at the front of the machine for varying the stop to utilize party-colored ribbons; an adjustable stop with a lever connected to act upon the lever-arm 37 and depress the ribbon guide below the printing point; a yielding means with connections to be actuated from the key levers of the typewriter, whereby the extent of actuation is controlled.

actuation by cam 4, thereby securing oscillation of the ribbon vibrator guide; a spring 51 for supporting arm 12'; adjustable stop means for the lever-arm 37 with its offset portion; an adjustable stop lever with a lever connected to act upon the lever-arm 37 and depress the ribbon guide below the printing point; and a yielding means with connections to be actuated therefrom to the key levers, of the typewriter, whereby the extent of actuation is controlled, all coacting substantially as described and for the purpose specified.

15. In a ribbon mechanism for typewriters, the combination of the frame; a ribbon spool upon a suitable shaft; a face cam 4 on the face of the ribbon spool and rotatable therewith; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement in conjunction with adjustable stop means; a swinging arm 7 pivoted in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; an arm 12' on the said rock shaft 12 with a pin 13' engaging the slot 13 in the link 9, whereby on rotating the shaft 12, the shoe 8 will be thrown out of or into contact with the cam 4, the stop 14 being arranged to limit the motion of the lever-arm 37 in varying degree, owing to its actuation by cam 4, thereby securing oscillation of the ribbon vibrator guide; and a yielding means with connections to be actuated from the key levers of the typewriter, whereby the extent of actuation is controlled, all coacting substantially as described and for the purpose specified.

16. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a variable stop means for the said lever-arm 37 controlled by a moving part of the machine, whereby oscillation of the ribbon is secured; a swinging plate 15; a link 20 connected thereto; a pair of levers 27—29 connected to the lower end of the said link, the lever 27 being fulcrumed back of the link and the lever 29 in front of

the link, whereby the depressing of the said lever will raise or lower the said link; a spring 46 connected to the stop pin 18 operating in a suitable slot to limit the motion of the said plate 15 and lock it either side of the center automatically; a stop 17 carried by the said adjustable plate 15 for contacting with the main part of the lever-arm 37; or the offset portion 37' therein, to permit the utilization of a party-colored ribbon; a stop 15' formed on the plate 15 for controlling the arm 12'; a stop formed on the arm 12' to control the plate 15 whereby it is impossible to swing the one into position without first swinging the other out of position; a lever 41 with an offset portion 42 for contacting with the said lever-arm 37; a plunger 43 with suitable notches on its upper side and having an actuating button 43' for controlling the said lever 41 for throwing the lever-arm 37 forward and depressing the ribbon guide of the printing position; a spring 44 for throwing the said plunger 43 upwards to engage the catch 45; and a yielding means with connections to be actuated from the key levers of the typewriter, whereby the extent of actuation is controlled, all coacting substantially as described and for the purpose specified.

17. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a variable stop means for the said lever-arm 37 controlled by a moving part of the machine, whereby oscillation of the ribbon is secured; adjustable stop means for the lever-arm 37 with its offset portion; connections to the key levers at the front of the machine for varying the stop to utilize party-colored ribbons; an adjustable stop with a lever connected to act upon the lever-arm 37 and depress the ribbon guide below the printing point; and a yielding means with connections to be actuated from the key levers of the typewriter, whereby the extent of actuation is controlled, all coacting substantially as described and for the purpose specified.

18. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a vari-

able stop means for the said lever-arm 37 controlled by a moving part of the machine, whereby oscillation of the ribbon is secured; adjustable stop means for the lever-arm 37 with its offset portion; connections to the key levers at the front of the machine for varying the stop to utilize party-colored ribbons; and a yielding means with connections to be actuated from the key levers of the typewriter, where the extent of actuation is controlled, all coacting substantially as described and for the purpose specified.

19. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; a variable stop means for the said lever-arm 37 controlled by a moving part of the machine, whereby oscillation of the ribbon is secured; adjustable stop means for the lever-arm 37 with its offset portion; an adjustable stop with a lever connected to act upon the lever-arm 37 and depress the ribbon guide below the printing point; and a yielding means with connections to be actuated from the key levers of the typewriters, all coacting substantially as described and for the purpose specified.

20. In a ribbon mechanism for typewriters, the combination of the frame; a ribbon spool upon a suitable shaft; a ribbon oscillator or vibrator consisting of arms 39 and the downwardly bent portion 40 supported on a suitable rock shaft 38; arranged in the upper front part of the machine; a downwardly-extending lever-arm 37 with its lower portion 37' offset from the main lever-arm to secure variation in movement, in conjunction with adjustable stop means; variable stop means for the said lever-arm 37 controlled by a moving part of the machine, whereby oscillation of the ribbon is secured; and a yielding means with connections to be actuated from the key levers of the typewriter whereby the extent of actuation is controlled, all coacting substantially as described and for the purpose specified.

21. In a ribbon mechanism for typewriters, the combination of the frame; a ribbon spool upon a suitable shaft; a face cam 4 on the ribbon spool shaft and rotatable therewith; a rock shaft 38 in the upper front part of the machine; a ribbon oscillator or vibrator consisting of arms 39 and the downwardly-extending bent portion 40 supported on the rock shaft 38; a downwardly-extending lever-arm 37 on said rock shaft; a swinging arm 7 pivoted in the upper part of the machine and terminating in the upper part of the

machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; an arm 12' on the said rock shaft 12 with a pin 13' engaging the slot 13 in the link 9, whereby, on rotating the shaft 12, the shoe 8 will be thrown into or out of contact with the cam 4, the stop 14 being arranged to limit the motion of the lever-arm 37 in varying degree owing to its actuation by the cam 4, thereby securing oscillation of the ribbon vibrator guide; and a spring catch 51 for supporting the arm 12', all co-acting substantially as described and for the purpose specified.

22. In a ribbon mechanism for typewriters, the combination of the frame; a ribbon spool upon a suitable shaft; a face cam 4 on the ribbon spool shaft and rotatable therewith; a rock shaft 38 in the upper front part of the machine; a ribbon oscillator or vibrator consisting of arms 39 and the downwardly-extending bent portion 40 supported on the rock shaft 38; a downwardly-extending lever-arm 37 on said rock shaft; a swinging arm 7 pivoted in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9; a rock shaft 12 with a knurled button 53 at its outer end for actuating the same; an arm 12' on the said rock shaft 12 with a pin 13' engaging the slot 13 in the link 9, whereby on rotating the shaft 12, the shoe 8 will be thrown into or out of contact with the cam 4, the stop 14 being arranged to limit the motion of the lever-arm 37 in varying degree owing to its actuation by cam 4, thereby securing oscillation of the ribbon vibrator guide, all co-acting substantially as described and for the purpose specified.

23. In a ribbon mechanism for typewriters, the combination of the frame; a ribbon spool upon a suitable shaft; a face cam 4 on the ribbon spool shaft and rotatable therewith; a rock shaft 38 in the upper front part of the machine; a ribbon oscillator or vibrator consisting of arms 39 and the downwardly-extending bent portion 40 supported on the rock shaft 38; a downwardly-extending lever-arm 37 on said rock shaft; a swinging arm 7 pivoted in the upper part of the machine and terminating in a suitable shoe 8 at its lower end to rest against the face cam; a horizontal link 9 carrying an adjustable stop 14 at its forward end, supported on a suitable flange 11, a slot 13 being formed in said link 9, thereby securing oscillation of the ribbon vibrator guide, all co-acting substantially as described and for the purpose specified.

tially as described and for the purpose specified.

24. In a ribbon mechanism for typewriters, the combination of the frame; a ribbon spool upon a suitable shaft; a face cam 4 on the ribbon spool shaft and rotatable therewith; a rock shaft 38 in the upper front part of the machine; a ribbon oscillator or vibrator consisting of arms 39 and the downwardly-extending bent portion 40 supported on the rock shaft 38; a downwardly-extending lever-arm 37 on said rock shaft; a swinging arm 7 pivoted in the upper part of the machine and terminating in a suitable shoe 8 at its lower end to rest against the face cam; and connections between the said shoe and the said downwardly-extending arm, thereby securing oscillation of the ribbon vibrator guide, all co-acting substantially as described and for the purpose specified.

25. In a ribbon mechanism for typewriters, the combination of the frame; a ribbon spool and its supporting shaft; a cam carried thereby; a ribbon oscillator or vibrator on a suitable rock shaft; a lever-arm from the rock shaft; a shoe arranged to rest against the cam and be actuated thereby; and connections between the shoe and the arm of the oscillator or vibrator, all co-acting substantially as described and for the purpose specified.

26. In a ribbon mechanism for typewriters, the combination of the frame; a ribbon spool on a suitable shaft; a cam carried by the said ribbon shaft and rotatable therewith; a ribbon oscillator with a suitable guide for the ribbon; a shoe to rest against the cam; and connections between the shoe and the oscillator whereby the ribbon is oscillated to utilize the width of the ribbon, coacting as specified.

27. In a ribbon mechanism for typewriters, the combination of the frame; a ribbon spool upon a suitable shaft; a rock shaft 38 in the upper front part of the machine; a ribbon oscillator or vibrator consisting of the arm 39 and the downwardly bent portion 40 supported on the rock-shaft 38; a downwardly-extending lever-arm 37 with its lower portion 37' offset from the main lever-arm to secure variation of movement; a swinging-plate 15; a link 20 connected thereto; a pair of levers 27—29 connected to the lower end of the said link, the lever 27 being fulcrumed back of the link and the lever 29 in front of the link, whereby the depressing of the said levers will raise or lower the said link; a spring 46 connected to the stop-pin 18 operating in a suitable slot to limit the motion of the said plate 15 and lock it either side of the center automatically; a stop carried by the said adjustable plate 15 for contacting with the main part of the lever-arm 37, or the offset portion 37' thereof, to permit the utilization of a party-colored ribbon; a lever 41 with an offset portion 42 for contacting with the said lever-arm 37; a plunger 43 with suitable notches on

its upper side and having an actuating button 43' controlling the said lever 41 for throwing the lever-arm 37 forward and depressing the ribbon-guide out of the printing position; and a spring 44 for throwing the said plunger 43 upwards to engage the catch 45, all co-acting substantially as described and for the purpose specified.

28. In a ribbon mechanism for typewriters, the combination of the frame; a ribbon spool upon a suitable shaft; a rock shaft 38 in the upper front part of the machine; a ribbon oscillator or vibrator consisting of the arm 39 and the downwardly bent portion 40 supported on the rock shaft 38; a downwardly-extending lever-arm 37 with its lower portion 37' offset from the main lever-arm to secure variation of movement; a swinging plate 15; a link 20 connected thereto; a pair of levers 27—29 connected to the lower end of said link, the lever 27 being fulcrumed back of the link and the lever 29 in front of the link, whereby the depressing of the said levers will raise or lower the said link; a stop carried by the said adjustable plate 15 for contacting with the main part of the lever-arm 37, or the offset portion 37' thereof, to permit the utilization of a party-colored ribbon; a lever 41 with an offset portion 42 for contacting with the said lever-arm 37; a plunger 43 with suitable notches on its upper side and having an actuating button 43' controlling the said lever 41 for throwing the lever-arm 37 forward and depressing the ribbon guide out of the printing position; and a spring 44 for throwing the said plunger 43 upwards to engage the catch 45, all co-acting substantially as described and for the purpose specified.

29. In a ribbon mechanism for typewriters, the combination of the frame; a ribbon spool upon a suitable shaft; a rock shaft 38 in the upper front part of the machine; a ribbon oscillator or vibrator consisting of the arm 39 and the downwardly bent portion 40 supported on the rock shaft 38; a downwardly-extending lever-arm 37 with its lower portion 37' offset from the main lever-arm to secure variation of movement; a swinging plate 15; a link 20 connected thereto; a pair of levers 27—29 connected to the lower end of the said link, the lever 27 being fulcrumed back of the link and the lever 29 in front of the link, whereby the depressing of the said levers will raise or lower the said link; a spring 46 connected to the stop pin 18, operating in a suitable slot to limit the motion of the said plate 15 and lock it either side of the center automatically; a stop carried by the said adjustable plate 15 for contacting with the main part of the lever-arm 37, or the offset portion 37' thereof, to permit the utilization of a party-colored ribbon, all co-acting substantially as described and for the purpose specified.

30. In a ribbon mechanism for typewriters, the combination of the frame; a ribbon spool upon a suitable shaft; a rock shaft 38 in the upper front part of the machine; a ribbon oscillator or vibrator consisting of the arm 39 and the downwardly bent portion 40 supported on the rock shaft 38; a downwardly-extending lever-arm 37 with its lower portion 37' offset from the main lever-arm 37 to secure variation of movement; a swinging plate 15; a link 20 connected thereto; a pair of levers 27—29 connected to the lower end of the said link, the lever 27 being fulcrumed back of the link and the lever 29 in front of the link, whereby the depressing of the said levers will raise or lower the said link; and an automatic lock for said plate 15, all coacting substantially as described and for the purpose specified.
31. In the ribbon mechanism for typewriters, the combination with the frame, of a ribbon spool with suitable guides; a ribbon oscillator at the front of the printing-point of the platen; key levers with yielding connections to said oscillator for actuating the same; adjustable stops for said oscillator; a pair of key buttons arranged at the left-hand of the key-board, with levers attached thereto, connected to said stops to control the amount of oscillation, whereby portions of the ribbon to each side of a central dividing line may be utilized, as for bi-chrome work, as specified.
32. In the ribbon mechanism for typewriters, the combination with the frame of a ribbon spool with suitable guides; a ribbon oscillator at the front of the printing point of the platen; key levers with yielding connections to said adjustable oscillator for actuating the same; adjustable stops for said oscillator; a pair of key buttons with levers attached thereto, connected to said stops to control the amount of oscillation, whereby portions of the ribbon to each side of a central dividing line may be utilized, as for bi-chrome work, as specified.
33. In a ribbon mechanism for typewriters, the combination of the frame; a ribbon spool upon a suitable shaft; a rock shaft 38 in the upper front part of the machine; a ribbon oscillator or vibrator consisting of the arm 39 and the downwardly bent portion 40 supported on the rock shaft 38; a downwardly-extending lever-arm 37; a lever 41 with an offset portion 42 for contacting with the said lever-arm 37; a plunger 43 with suitable notches on its upper side and having an actuating button 43' controlling the said lever 41 for throwing the lever-arm 37 forward and depressing the ribbon out of the printing position; and a suitable catch to retain said plunger in place, all co-acting substantially as described and for the purpose specified.
34. In a ribbon mechanism for typewriters, the combination of the frame; a ribbon spool upon a suitable shaft; a rock shaft 38 in the upper front part of the machine; a ribbon oscillator or vibrator consisting of the arm 39 and the downwardly bent portion 40 supported on the rock shaft 38; a downwardly-extending lever-arm 37; a lever 41 with an offset portion 42 for contacting with the said lever-arm 37; a plunger 43 with suitable notches on its upper side and having an actuating button 43' controlling the said lever 41 for throwing the lever-arm 37 forward and depressing the ribbon out of the printing position; and a suitable catch to retain said plunger in place, all co-acting substantially as described and for the purpose specified.
35. In a ribbon mechanism for typewriters, the combination with the frame of a suitably supported ribbon spool; a ribbon oscillator consisting of the arm 39 and the downwardly-bent guide portion 40 suitably supported in the upper front part of the machine; a downwardly extending lever arm 37 for controlling the said ribbon oscillator; a plunger 43 having an actuating button 43'; connections from said plunger for throwing the said lever arm 37 forward and depressing the ribbon guide out of the printing position; and adjusting catch means for said plunger, whereby when the catch is released the ribbon vibrator is free to operate in its different positions, co-acting for the purpose specified.
36. In a ribbon mechanism for typewriters, the combination with the frame of a suitably supported ribbon spool; an oscillating guide for the ribbon to guide the ribbon to the printing position; yielding means for oscillating the said guide; a plunger having a suitable actuating button at the front of the machine; connections to the said plunger for depressing the ribbon guide out of printing position; and adjusting catch means for said plunger, whereby when the catch is released the ribbon vibrator is free to operate in its different positions, co-acting for the purpose specified.
37. In a ribbon mechanism for typewriters, the combination with the frame of a suitably supported ribbon spool; an oscillating guide for the ribbon to guide the ribbon to the printing position; yielding means for oscillating the said guide; a plunger having a suitable actuating button at the front of the machine; connections to the said plunger for depressing the ribbon guide out of printing position; and adjusting catch means for said plunger, whereby when the catch is released the ribbon vibrator is free to operate in its different positions, co-acting for the purpose specified.
38. In a ribbon mechanism for a typewriter, the combination with the frame of a

suitably supported ribbon spool; an oscillating guide for the ribbon to guide the ribbon to the printing position; means for oscillating the said guide; a plunger having a suitable actuating button at the front of the machine; connections to the said plunger for depressing the ribbon guide out of printing position; and adjusting catch means for said plunger, whereby when the catch is released the ribbon vibrator is free to operate in its different positions, co-acting for the purpose specified.

39. In a ribbon mechanism for a typewriter, the combination with the frame of a suitably supported ribbon spool; an oscillating guide for the ribbon to guide the

ribbon to the printing position; means for oscillating the ribbon guide; adjustable connections arranged to be operated from the front of the machine for holding the said oscillating guide in a depressed position; a suitable catch therefor, whereby, when the catch is released the ribbon vibrator is free to operate in its different positions below the printing point.

In witness whereof, I have hereunto set my hand and seal in the presence of two witnesses.

WILLIAM R. FOX. [L. s.]

Witnesses:

ELLA DE VRIES,
LELIA BLAIN.
